UNITED STATES PATENT OFFICE.

HORACE PRESTON LIVERSIDGE, OF BALA, PENNSYLVANIA, ASSIGNOR TO PENNSYLVANIA APPLIANCE COMPANY, OF PHILADELPHIA, PENNSYLVANIA, A CORPORATION OF NEW JERSEY.

ELECTRIC FUSIBLE CUT-CUT.

1,124,230.

Specification of Letters Patent.

Patented Jan. 5, 1915.

Application filed April 9, 1913. Serial No. 759,886.

To all whom it may concern:

Be it known that I, HORACE PRESTON LIVERSIDGE, of Bala, in the county of Montgomery and State of Pennsylvania, have invented certain new and useful Improvements in Electric Fusible Cut-Outs, whereof the following is a specification, reference being had to the accompanying drawings.

My invention relates to a fusible cut-out 10 for electric circuits of the expulsion type, in which the fusing of the cut-out by which the circuit is broken, releases a compressed gas or liquid, which is thereupon expelled with sufficient force to blow out the electric 15 arc otherwise formed upon the breaking of the electric circuit.

It has heretofore been proposed to construct so-called expulsion fuses in which the heat of an arc if formed releases compressed 20 gas and blows out the arc; but in such cases, the release of the compressed gas has been effected by the employment to confine the gas, of a fusible plug, not in the electric circuit itself, but merely in proximity to the 25 fusible section of the electric circuit, so that the formation of an arc by the melting of a portion of such circuit, may communicate sufficient heat to melt the fusible plug which restrains the compressed gas; but in such 30 constructions the release of gas is uncertain, since the heat of the arc may not melt the fusible plug.

It is characteristic of my invention that I make the fusible portion of the electric 35 circuit itself the means of restraining the compressed fluid, so that the melting and consequent breaking of the circuit of necessity effects the release of the fluid.

In the accompanying drawings, Figure I, 40 is a plan view of a fusible cut-out embodying my invention. Fig. II, is a vertical longitudinal section of the same. Fig. III, is an end elevation with the receptacle for holding the container for the compressed 45 gas opened.

In the accompanying drawings, the holder or casing 1, is provided with a pivoted end piece 2, which carries the links 3, pivot 4, and handle 5. It may be secured in closed position by placing the pivot 4, beneath the lug 6. Other means for closing the holder may be employed. To the open end of the holder is attached an insulating sleeve 10, the other end of which is provided with a suitable 55 contact terminal 11. A second contact ter-

minal 12, is attached to or forms a part of the holder 1, so that the two contact terminals are separated by the insulating sleeve 10.

The interior of the holder 1, is shaped to 60 contain the metallic receptacle 15, containing compressed fluid. To the open end of this receptacle is attached a metallic tube 16, the end of the tube being expanded within the contracted opening of the receptacle 65 to form a hermetically closed joint. The metallic tube 16, is of electrically conductive metal and (in part at least) fusible. It is provided with a restricted area 17, beyond which it is closed at 18, by means of a metal 70 clamp 19, which is connected by the wire 20, to the binding clamp 21, electrically connected to the contact terminal 11. Similarly the metal contact pipe 30, which is electrically connected to the contact terminal 75 12, is clamped around the tube 16, near the end which is attached to the receptacle 15. The fusible tube 16, is surrounded by a larger tube 33, of electrically non-conducting refractory material, such as asbestos, 80 which forms a protector and facilitates the blowing out of the fuse.

The fusible tube 16, forms a part of the electric circuit which connects the contacts 11, and 12, as has been above explained. 85 The narrowed portion of the tube is the point which will first melt in case the tube becomes overheated from carrying a heavier electrical current than that for which it is intended. In case of the melting of the 90 tube 16, the compressed fluid preferably carbon-dioxide, contained within the receptacle 15, and the tube 16, necessarily finds an outlet at the point of fusion. The fluid thus escaping forms a blast of considerable force 95 which instantly blows the loose end of the tube 16, out of the end of the tube 33. This effectually prevents the formation of any arc, since the volatile gases upon which the formation of an arc is dependent, are instantly dissipated by the explosive force of the escaping fluid. Furthermore, the escaping fluid by reason of its expansion cools down the point where the circuit is broken preventing volatilization. It will be noted 100 that certain and efficient action of the expelled fluid is compelled by the fact that a part of the container of the fluid, that is the tube 16, itself forms a part of the electrical circuit, so that the melting of the fusible 11

portion of this circuit, to break the circuit, of itself releases the fluid, without the necessity of the further communication of heat resulting from the formation of an arc to a 5 second fusible piece, by which compressed gas is restrained, as has heretofore been suggested in previous expulsion fuses.

Having thus described my invention, I claim:

- 10 1. A fusible cut-out for safeguarding electric circuits comprising a metallic receptacle for a compressed fluid, a portion of said receptacle being fusible, said receptacle and its fusible portion both forming a part of the circuit to be safeguarded.
- 15 2. A metallic receptacle containing fluid under pressure provided with an aperture closed by a prolonged structure of fusible metal, said receptacle and the prolonged 20 structure which closes it forming successive parts of a continuous permanent electrical

conductor, the overheating of which by excessive current melts the fusible metal structure and simultaneously releases fluid pressure from the metallic receptacle.

3. A fusible cut-out for electric circuits comprising a metallic receptacle for a compressed fluid; a fusible extension thereon, the melting of which opens the receptacle, an electric circuit of which said receptacle 30 and its fusible extension form continuous parts, and a larger tube surrounding said tubular extension open at the end away from the receptacle.

In testimony whereof, I have hereunto 35 signed my name at Philadelphia, Pennsylvania, this fifth day of April, 1913.

HORACE PRESTON LIVERSIDGE.
